(57) CLAIM

The ornamental design for an EYEWEAR CLEANING KIT CONTAINER as shown and described.

DESCRIPTION

FIG. 1 is a perspective view of an eyewear cleaning kit showing my new design;

FIG. 2 is a front view thereof;

FIG. 3 is a back view thereof;

FIG. 4 is left side view thereof;

FIG. 5 is right side view thereof;

FIG. 6 is a top view thereof; and

FIG. 7 is a front view of the eyewear cleaning kit of FIG. 1, with the top cap removed and showing the spray bottle and nozzle of the eyewear cleaning kit.

The broken lines in the drawings illustrate unclaimed subject matter and form no part of the claimed design.
